SLICING MACHINE

Filed Nov. 21, 1930

Fig. 1.

UNITED STATES PATENT OFFICE

GOTTLIEB F. ESSIG, OF PHILADELPHIA, PENNSYLVANIA

SLICING MACHINE

Application filed November 21, 1930. Serial No. 497,169.

The object of this invention is to devise a novel construction and arrangement of a slicing machine wherein the slicing operation is effected by the movement of an article container, for the material to be sliced, in one direction or in an opposite direction.

A further object of the invention is to devise a novel slicing machine of the character stated wherein the article container has an open bottom and travels over a fixed knife having cutting edges at opposite sides and wherein the articles in the container are supported by a belt moving in the same direction as the article container to support the articles therein.

15 A further object of the invention is to devise novel means for preventing the cut material accumulating at the cutting edges of the knife, and, as illustrated, this means is in the form of bars connected with endless aprons traveling in proximity to the cutting edges of the knife.

With the above and other objects in view, my invention comprehends a novel slicing machine wherein a reciprocatory motion is imparted to an article container which travels across a fixed knife having cutting edges on opposite sides and wherein the bottom of the article container is formed by traveling belts which support the articles to be sliced which are in the article container.

It further comprehends a novel construction and arrangement of cutting mechanism, an article container, and endless belts which travel in the same direction and preferably at the same speed as the article container and which are provided with means for wiping the cutting edges of the knife.

Other novel features of construction and advantage will hereinafter more clearly appear in the detailed description and the appended claims.

For the purpose of illustrating the invention I have shown in the accompanying drawings a typical embodiment of it, which,

in practice, will give reliable and satisfactory results. It is, however, to be understood that this embodiment is typical only and that the various instrumentalities of which my invention consists can be variously arranged and organized, and the invention is not limited to the precise arrangement and organization of these instrumentalities as herein set forth.

Figure 1 is a top plan view of a slicing machine embodying my invention.

Figure 2 is a side elevation of a portion of the machine.

Figure 3 is a section on line 3—3 of Figure 1.

Similar numerals of reference indicate corresponding parts.

Referring to the drawings:

1 designates a supporting frame of any desired character, which, as illustrated, consists of standards 2 connected with end bars 3 to which are connected the side bars 4 thereby forming a rectangular framework. The side bars 4 are provided with grooves 5 in their inner sides to receive the rollers 6 carried by the article container 7. This article container 7 may have any desired contour in cross section, but, as illustrated, is rectangular and provided with an open top and an open bottom.

8 designates a stationary knife which is provided at each side with a cutting edge 9 so that when the article container is moved in either a forward or a reverse direction the articles contained therein will be cut by one or the other of the cutting edges of the stationary knife 8. The article container has connected with it, in any desired manner, a rack 10 which meshes with the pinions 11 carried by shafts 12. The shafts 12 are provided with rollers 13 around one of which passes an endless belt 14 and around the other of which passes an endless belt 15. The belt 14 also passes around a roller 16 journaled in the machine frame and in a similar man-

ner the belt 15 passes around a roller 17 journaled in the machine frame. This provides two endless belts which are driven by the revolution of their respective shafts 12 as the article container 7 moves forwardly or rearwardly. The belt 14 is provided with an upwardly extending rib 18 and in a similar manner the belt 15 is provided with an upwardly extending rib 19. These ribs 18 and 19 serve to wipe the juxtaposed edges of the stationary knife 8 and prevent any accumulation of the cut material thereon.

The article container 7 may be reciprocated in any desired manner. For the purpose of illustration, I have shown an electric motor 20 provided with a disc 21 to which is eccentrically connected one end of a connecting rod 22, the opposite end of which is connected at 23, to the rack 10. Of course, this driving connection might be connected to either of the shafts of the rollers 16 or 17, or in any other desired manner to the article container 7 to effect the reciprocations of the latter.

In the operation of my device, it will be apparent that when the motor is started it will effect the reciprocatory movement of the rack 10 and the article container 7 to which it is connected so that the article container will pass to and fro over the stationary knife 8. As the rack 10 is in mesh with the pinions 11, it will cause the revolution of the shafts 12, thereby driving their rollers 13 and the endless belts 14 and 15.

It will thus be clear that if the article container 7 is filled with material to be cut, the material will be cut as it passes over the stationary knife 8 in one direction, by one cutting edge of the knife, and, as it moves in the opposite direction, the material will be cut by the other cutting edge of the stationary knife. As the article container moves, for example, towards the knife, it will be apparent that the belt beneath it will close the bottom of the container so that a closed bottom is formed moving in the same direction and at the same speed as the article container. As the article container moves over the stationary knife 8 it will be apparent that the endless belt on the opposite side acts in the same way to form a closed bottom for the article container.

In each forward or reverse movement of an endless belt 14 or 15, it will be apparent that the ribs 18 and 19 have a wiping contact with the cutting edges 9 of the stationary knife 8 so that these cutting edges are always retained in proper cutting condition. The cut material passes downwardly between the belts and the stationary knife into a receptacle, not shown, placed beneath such opening to receive the material which has been sliced or cut.

It will now be apparent that I have devised a new and useful slicing machine which

embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. In a slicing machine, a frame, an article container slidably mounted therein for reciprocatory movement and having its bottom open, a pair of endless belts mounted in said frame over which said article container reciprocates, a fixed knife having cutting edges at opposite sides positioned between the juxtaposed ends of said belts, and means to effect the reciprocation of said article container.

2. In a slicing machine, a reciprocatory article container having an open bottom, a stationary knife having at opposite sides cutting edges and over which said container reciprocates, endless belts having one end juxtaposed in proximity to said knife to form, during the movement of the article container, a closed bottom therefor, said belts being interconnected to move in the same direction, and means to effect the reciprocation of said article container over said belts and said stationary knife.

3. In a slicing machine, a frame, a fixed knife therein having cutting edges at opposite sides, endless belts mounted in said frame and having one end juxtaposed to a cutting edge of said knife, each of said belts having a raised rib to form a wiping member cooperating with the juxtaposed cutting edge of said knife, an article container having an open bottom, and means to effect the reciprocatory movement of said article container and to cause each of said belts to move in the same direction and at the same speed as the direction and speed of movement of the article container.

4. In a slicing machine, a frame, a fixed knife therein having cutting edges at opposite sides, rollers carried by said frame, endless belts cooperating with said rollers, the rollers at one end of the belts being juxtaposed to the stationary knife and provided with shafts, an article container guided in said frame to travel across said stationary knife, means to operatively connect said article container with said shafts whereby the latter will be driven in unison with and in the same direction as the direction of movement of the article container, and means to effect the reciprocatory movement of said article container.

5. In a slicing machine, a frame, a fixed

knife having cutting edges at opposite sides carried by said frame intermediate its ends, an article container having an open bottom guided in said frame to travel over said knife, 5 shafts journaled in said frame, endless belts driven by said shafts to close the bottom of said article container during its reciprocatory movement, a rack and pinion connection with said belts, an article container to 10 cause them to move in unison with each other, and means to effect the travel of said belts and thereby the reciprocatory movement of the article container.
